(57) **CLAIM**

The ornamental design for a storage container, as shown and described.

DESCRIPTION

FIG. 1 is a perspective view of a storage container showing our new design;

FIG. 2 is a bottom perspective view of the storage container illustrated in FIG. 1;

FIG. 3 is left side view of the storage container illustrated in FIG. 1;

FIG. 4 is a front view of the storage container illustrated in FIG. 1;

FIG. 5 is a right side view of the storage container illustrated in FIG. 1;

FIG. 6 is a rear view of the storage container illustrated in FIG. 1;

FIG. 7 is a top view of the storage container illustrated in FIG. 1; and,

FIG. 8 is a bottom view of the storage container illustrated in FIG. 1.

The evenly-dashed broken lines illustrate portions of the storage container that form no part of the claimed design. The dash-dot broken lines illustrate the boundary of the design and form no part of the claimed design.

1 Claim, 4 Drawing Sheets

Related U.S. Application Data

continuation-in-part of application No. 29/580,170, filed on Oct. 6, 2016, now Pat. No. Des. 863,055, and a continuation-in-part of application No. 29/558,788, filed on Mar. 21, 2016, now abandoned.
